UNITED STATES PATENT OFFICE.

JOHN J. FITZGERALD, OF CHICAGO, ILLINOIS, ASSIGNOR TO THE
FITZGERALD MEAT TREE COMPANY, OF SAME PLACE.

DESIGN FOR A MEAT-HANGER MEMBER.

SPECIFICATION forming part of Design No. 31,309, dated August 1, 1899.

Application filed January 16, 1899. Serial No. 702,365. Term of patent 14 years.

To all whom it may concern:

Be it known that I, JOHN J. FITZGERALD, a citizen of the United States, residing at Chicago, in the county of Cook and State of Illinois, have invented and produced a new and original Design for a Meat-Hanger Member, of which the following is a specification, reference being had to the accompanying drawings, forming part thereof.

10 Figure 1 is a bottom plan view of a meat-hanger member, showing my design. Fig. 2 is a view in side elevation. Fig. 3 is a view, partly in elevation and partly in section, taken on line 3 3 of Fig. 1, looking in the direction indicated by the arrows.

15 As shown in the drawings, the leading or

material feature of my design consists of two parallel bars or rails B, connected together at their middle portions by means of a cross-piece A, which has a vertical opening C through its middle. Each of the bars of rails B is provided with a series of projections a, located a short distance apart.

Having described my invention, what I claim as new, and desire to secure by Letters 25 Patent, is—

The design for a meat-hanger member, substantially as herein shown and described.

JOHN J. FITZGERALD.
